UNITED STATES PATENT OFFICE.

CHESTER R. COX, OF BERKELEY, CALIFORNIA.

IRONING-BOARD CABINET.

1,110,903.

Specification of Letters Patent. Patented Sept. 15, 1914.

Application filed July 22, 1912. Serial No. 710,960.

To all whom it may concern:

Be it known that I, CHESTER R. Cox, residing in the city of Berkeley, county of Alameda, State of California, United States 5 of America, have invented a new and useful Improvement in Ironing-Board Cabinets, of which the following is a full and complete description.

The invention contemplates the use of and
10 has for its object the saving of room when
the ironing board is not in use, and by its
mechanical construction can be built in a
four inch partition or can be screwed fast
to the wall as desired.

15 Referring to the accompanying drawings which form a part of this specification— Figure 1 is a perspective view showing the ironing board exposed and extended for use. Fig. 2 is a vertical section of the board and its receptacle. Fig. 3 is a vertical section of the cabinet showing the ironing board in extended position.

In the drawing 2 designates the ironing board, the back end of which has a rounded shaft. 3.

4 are channels or grooves in the sides of the jambs A to receive the ends of shaft 3 of the ironing board; the shaft being left full size at each end and beyond the sides 30 of the ironing board sufficiently long to guide the board down into the pocket and to work in the grooves 4 cut in the sides of the jambs.

5 is a door hinged below the board 2, which acts as a support to the ironing board, when extended and in use, and also closes up the front of the opening when the board is in the pocket, being hinged at 6.

13 is a door hinged, as shown, to swing to the left, and, together with support 5, closes up the entire front of the device when the ironing board is not in use.

The channels or grooves 4 in the jambs A form guides for the ironing board as it is being manipulated. These channels terminate slightly above the height of the level of the ironing board, when extended, thereby preventing shaft 3 from going higher.

7 is a batten on the bottom of the ironing board for the door 5 to rest against.

The spring hinges 6 are of any well-known construction and serve to automatically close the door 5 when the board 2 is folded into the receptacle. A sleeve board 8 may be 55 journaled in the jambs above the board 2

and sufficiently to the rear of the vertical line of the journals of the board 2 to allow the two boards to be turned up vertically within the receptacle without interference.

9 is a round end and has the same relation to the sleeve board that the shaft 3 has to the main ironing board, being let into the jamb at each end merely for support.

10 is the support for the sleeve board when in use and is hinged to drop down when the board is folded in the pocket. 65

12 is a pin for the purpose of holding the back end of the ironing board firm, when in use, and supporting the shaft 3. The pin 12 projects from the side of the shaft 3 and is adapted to drop into an aperture shown in the retaining spring 11, Fig. 3, when the board has reached a level position. 70

The shaft 3 at the inner end of the board 2 projects into and is guided by the grooves 4 in the sides of the receptacle. When the board is tilted outward to assume a horizontal position the lug or batten 7 first contacts with the top of the door 5 which then swings outward about the hinge 6, and the shaft 3 slides upward at the same time until the ironing board 2 has assumed a horizontal position and the inner end is engaged by the retaining spring 11. 75 80

To close the board into the pocket, the inner end is disengaged from the holding device and the outer end is lifted so that the board may slide downward until its upper end will enter the upper part of the pocket. The sleeve board is closed up at the same time and the spring door 5 closes behind the lower part of the board. The upper part of the pocket may then be closed by the door 13. A backing is fitted to the frame to make it dust-proof. 95

Having thus described my invention, what I claim and desire to secure by Letters Patent is—

In a device of the character described, a receptacle having a hinged, transversely swinging door at the top, and a door hinged at the bottom to open outwardly and downwardly, said doors closable to form a continuous paneled front for the receptacle, a jamb on each side of the receptacle having a vertical channel in the lower part, an ironing board having a cylindrical rear end, projecting at each side forming journals slideable in the channels of the jambs, the upper ends of the channels forming stops for said 116

journals, and said board being turnable to project horizontally when opened, the lowermost door forming a fulcrum and an angular brace to support the outer end of the board when extended, an apertured retaining spring pressing against the cylindrical rear end of the board, and a pin in said end

of the board adapted to engage the aperture in the spring when registering therewith.

CHESTER R. COX. [L.S.]
